UNITED STATES PATENT OFFICE.

JOHN F. GULYBAN, OF BEDFORD, OHIO.

COOLING AND HEATING SYSTEM FOR AUTOMOBILES.

Application filed January 2, 1925. Serial No. 240.

To all whom it may concern:

Be it known that I, JOHN F. GULYBAN, a citizen of the United States, and residing at Bedford, in the county of Cuyahoga and 5 State of Ohio, have invented certain new and useful Improvements in a Cooling and Heating System for Automobiles, of which the following is a specification.

My invention relates to an improvement 10 in a combined cooling and heating system for automobiles operated by internal combustion engines, and in general my object is to provide a simple hot water circulating system for heating the vehicle to comfortable temperatures in cold weather by utilizing a part or all of the water heated by the 15 engine. The invention is also particularly designed to circulate the hot water from the engine through the heaters in the car or 20 the water cooling radiator at the front of the car alternatively, and to cause the water passing through the engine to be diverted automatically through the cooling radiator when the water becomes too hot for efficient 25 operation of the engine.

In the accompanying drawings, Fig. 1 is a schematic view of an automobile embodying an internal-combustion engine having a gravity flow cooling and heating system constructed and arranged according to my invention.

Fig. 2 is an enlarged sectional view of the valved by-pass elbow used in my apparatus, and Fig. 3 is a sectional view of the 35 automatic device used at the water return manifold for controlling the by-pass valve shown in Fig. 2. Fig. 4 is a schematic drawing of an automobile embodying a pump operated circulating system constructed and 40 arranged according to my invention.

The present invention involves an automobile or other vehicle 2 in which an internal combustion engine 3 is used having a water jacket 4 through which a cooling 45 medium, such as water, is circulated while the engine is running. The water is cooled by discharging it from the top of the engine through a pipe connection 5 leading to the upper end of a cooling radiator 6, and thence 50 from the lower end of the radiator back to the engine by way of a return pipe 7 which connects with a detachable manifold or coupling member at one side of the water jacket. In some types of engines the circulation of water is caused by the heat gen-

erated in the water jacket, (see Fig. 1), and in other types, a mechanically operated pump P is employed, (see Fig. 4).

I substitute a water-intake coupling or manifold 8 of special construction for the 60 coupling or manifold generally attached to the engine, and mount a hollow screw-threaded cap or cover 9 in a sealed position upon the otherwise open top or coupling member 8, which member has a central 65 screw-threaded bridge 10 adapted to support an expansible thermostatic element T within cap 9 opposite a lateral outlet port and pipe 11, (see Fig. 3). Thermostatic element T is provided with a vertical stem 70 12 which extends through a packing gland 13 in the top of cover 9 where the short arm 14 of a pivoted lever 15 is adapted to be loosely engaged and raised by the stem when the thermostatic element is heated and expanded by hot water returning at high temperature to water-jacket through coupling member 8 by way of return pipe 7 from cooling radiator 6 or by way of return pipe 11 from the heating coil 16 within the vehicle. To effect circulation of the hot water through heater 16 I provide a separate elbow member 17 at the outlet end of the water jacket of the engine and connect an intake pipe 18 for the heater with a lateral branch 19 on elbow member 17. A pivoted valve member 20 within this elbow member is adapted to divert the flow of water either to the radiator pipe 5 or to the heater pipe 18, dependent upon conditions in the engine 90 and the movement of a bell crank 21 which is mounted outside of valve 20 and connected to the valve. The bell crank may be actuated manually or automatically, and the manual operation is effected by an operating 95 rod 22 which connects with one arm of the bell crank 21 and extends into the interior of the car where the driver may press it inward to close the by-pass branch 19 and heater pipe 18 when a flow of hot water 100 through the heater is not desired. A lug or catch 23 may be fixed on rod 22 adjacent the edge of a slot 24 in the instrument board 25 so that when the rod is pressed inward at its limit the catch will hold the rod against a return movement providing it is permitted to gravitate into locking engagement with the bottom edge of slot 24. Automatic operation of valve 20 is effected by a link 26 connected to the long arm of lever 15 which is 110

actuated by thermostatic device T when the water becomes too hot for efficient operation of the engine and it becomes desirable or necessary to pass the water through cooling radiator 6 instead of heater 16. Thus, a coiled spring 27 attached to lever 15 tends to raise the long arm of the lever and to hold valve 20 in a closed position across the main outlet 28 in elbow member 17. The 10 spring also holds the short end of the lever in contact with vertical stem 12 of thermostatic element T. As a result whenever the water in the engine jacket 4 becomes too hot it will cause the thermostatic device to 15 tilt lever 15 and open the outlet 28 leading to the cooling radiator, thereby establishing a flow of hot water from the engine to the radiator where it will be cooled before returning to the engine through pipe 7 and 20 coupling 8. A part of this water may be bypassed to heater 16 and a part to radiator 6 but when the temperature of the water is too high for efficient operation of the engine the flow to the heater is entirely cut off and 25 radiator 6 functions to lower the temperature until a part or all of the circulating water is again passed through the heater. A slotted connection 29 may be adjustably connected to rod 22 and bell crank 21 to 30 permit automatic movements of the parts without causing locking engagement of catch 23 with board 24. A water overflow pipe 30 may also be connected to pipe 18 or some other part of heater 16, and the top 35 of this overflow pipe may have an air opening or vent 31 to prevent siphoning of the contents of the system.

In Fig. 4 I show a water cooling and heating system in connection with an engine 40 32 having a water-circulating pump P, the return pipes 33 and 34 from radiator 35 and heater 36 being connected to the intake side of the pump, and the discharge side of the pump being connected by a pipe 37 with 45 coupling member 38. All the other parts correspond to the parts in the structure previously described and are designated by the same numerals and characters. In Fig. 1 the heater is shown in front of the driver's seat. Obviously the heater may be located 50 wherever most convenient and desirable. Also, two or more heaters may be used with this system, and the water may be heated to a high temperature for a plurality of heaters before causing the thermostatic device to by-pass the water through the cooling radiator.

What I claim is:

1. A cooling and heating system for 60 automobiles, comprising an internal-combustion engine having a water jacket, a cooling radiator having water circulating connections with said engine, a heater mounted upon said automobile having water-circulating connections with said engine, and 65

means adapted to effect circulation of the heated water through said radiator or heater alternatively.

2. A cooling and heating system for automobiles, comprising a water cooled engine and a radiator and heater in joint water circulating connection with said engine, in combination with a thermostatic device adapted to by-pass the hot water from said heater to said radiator when the 75 temperature of the water is too high for efficient working operations of the engine.

3. A cooling and heating system for automobiles, comprising a water cooled engine and a water cooling radiator and a 80 heater in water circulating connection with said engine, and said engine having a hot water discharge connection provided with branch passages and a valve adapted to control the flow of water therethrough.

4. A cooling and heating system for automobiles, comprising a water cooled engine and a water cooling radiator and a heater in water circulating connection with said engine, and said engine having a hot 90 water discharge connection provided with branch passages and a valve adapted to control the flow of water therethrough, and a thermostatic device adapted to control said valve.

5. A cooling and heating system for automobiles, comprising a water cooled engine and a cooling radiator in circulatory connection therewith, a heater in water circulating connection with said engine, a 100 valved by-pass member adapted to divert the water either through said radiator or said heater, a thermostatic device in the circulatory connections adapted to control said valved by-pass device, and a manually controlled element adapted to permit independent operation of said valved by-pass device.

6. A cooling and heating system for automobiles, comprising a water cooled engine and a cooling radiator in circulatory connection therewith, a heater in water circulating connection with said engine, a valved by-pass member adapted to divert the water either through said radiator or said 110 heater, a thermostatic device in the circulatory connections adapted to control said valved by-pass device, and a manually controlled element adapted to permit independent operation of said valved by-pass device, said manually controlled element having means associated therewith adapted to lock the same and said valved by-pass device to maintain open water circulating connection with the radiator and to render 115 said thermostatic device inoperative.

7. A cooling and heating system for automobiles, comprising a water cooled engine, a cooling radiator and water circulating connection for the engine, detachable 120

- coupling members for said connections having branch water circulating connections for a heater, a valve in one coupling member, a thermostatic device in another coupling member, operating connections between said thermostatic device and valve, and a heater coupled to said water circulating connections controlled by said valve and thermostatic device.
- 10 8. A cooling and heating system for automobiles, comprising a water cooled engine having an outlet elbow provided with a valved by-pass connection, a water intake manifold for said engine having a removable cover provided with a water circulating connection and containing a thermostatic device and carrying a pivoted lever adapted to be actuated by said thermostatic device, an operating connection between said lever and valved by-pass connection, and 20 independent cooling and heating radiators in common water circulating connection with said outlet elbow and intake member.
- 15 9. A cooling and heating system for automobiles, comprising a water intake manifold for a water cooled engine, a removable cover for said manifold containing an expansible thermostatic device, a lever in adjustable operating connection with said device, and a valve having operating connection with said lever and adapted to divert the outflow of water from said engine to different paths.
- 10 10. In testimony whereof I affix my signature.
- JOHN F. GULYBAN.
